FREDERICK C. MÜNCH, OF HULL, MASSACHUSETTS, AND ONE-HALF TO MAR-
CELLUS W. SPRINGER, OF CAMBRIDGE, MASSACHUSETTS.

SUPPORT FOR TELEPHONE-RECEIVERS.

1,119,366.

Specification of Letters Patent.

Patented Dec. 1, 1914.

Application filed June 23, 1913. Serial No. 775,208.

To all whom it may concern:

Be it known that I, HENRY W. MÜNCH, a citizen of the United States, residing at Arlington, county of Middlesex, State of Massachusetts, have invented an Improvement in Supports for Telephone-Receiver, of which the following description, in connection with the accompanying drawing, is a specification, like characters on the drawing representing like parts.

This invention has for its object to provide a novel support for a telephone receiver by which the receiver may be held at a person's ear while he is talking into the transmitter thus making it possible for said person to have the free use of both hands while using the telephone.

Devices for this general purpose have been heretofore devised and my present invention aims to produce a novel form of transmitter support all as will be more fully hereinafter described and then pointed out in the appended claims.

Referring now to the drawings wherein I have illustrated a selected embodiment of the invention from which the principle thereof will be readily discerned, Figure 1 is a front view of a so-called "desk stand" having a device embodying my invention applied thereto. Fig. 2 is a top plan view of Fig. 1. Fig. 3 is a right hand side elevation of the receiver support. Fig. 4 is the left hand elevation. Fig. 5 is an enlarged view partly in section showing the manner of attaching the device to the desk stand. Fig. 6 is a side view of the receiver support detached with the receiver sustained thereon. Fig. 7 is a fragmentary perspective view of the hook-depressing lever.

I have herein illustrated my invention as it would be applied to a so-called "desk stand set" but it will be readily understood that the invention may be applied to other types of telephones by making suitable modification in the structural details.

In the drawings I have indicated at 1 a desk stand having the usual transmitter 2 and receiver 3, said desk stand having the hook 4 on which the receiver is normally hung, all as usual. The transmitter 2 is pivotally connected to the stand or support 1 as usual and for this purpose the stand is provided with the two ears 5 between which is received a hub 6 on the transmitter head,

a pivotal clamping screw 7 extending through the ears and hub and serving to connect the transmitter to the stand. This pivotal clamping screw is provided with two washers 8 and 9 that bear against the outside of the ears 5 and it carries a clamping nut 10 by which the ears 5 may be frictionally clamped against the opposite faces of the hub 6, thereby to provide sufficient friction for holding the transmitter head in adjusted position. The ears 5 are shown as having extensions 11 which form stops to limit the upward movement of the transmitter, all as usual in telephone desk sets. The parts thus far described are or may be of any known construction and form no part of my present invention.

My improved receiver support comprises a receiver rest 12 which may conveniently be made of sheet metal stamped into a shape to fit and hold the receiver 3, and a supporting arm of novel construction by which the rest 12 is sustained by the stand or support 1. This supporting arm is shown at 13 and it is formed at one end with the laterally bent forked portion 14 that is adapted to embrace the pin 7 and to be clamped between the washer 9 and one of the ears 5. I will preferably provide the supporting arm 13 with the positioning projections 15, between which the extension 11 on the ear 5 is received said projections 15 operating to hold the supporting arm 13 in proper position and preventing it from turning about the pin 7. At the outer end the supporting arm 13 is provided with the adjustable extension 16 which is adjustably and pivotally connected to the arm 13 and to which the rest 12 is secured. Any suitable way of connecting the extension 16 to the arm 13 may be employed. As herein shown the extension 16 is provided with the slot 17 and the arm 13 is provided with a clamping bolt 19 having clamping nuts 18 thereon, which bolt extends through the slot 17 and by which the extension 16 is rigidly clamped to the arm 13. By loosening the clamping nuts 18, the arm 16 may be swung about the clamping bolt 19 into different angular positions or may be adjusted longitudinally of the slot 17 so as to bring the rest 12 in the desired position. The outer end of the extension 16 is down-turned as shown at 20 and said down-turned end is provided with

5 a clamping screw 21 which extends through a slot 22 in a down-turned ear 23 extending from the rest 12. This construction provides one whereby the rest can be adjusted vertically relative to the extension 16 and 10 may also be tilted about the clamping screw 21 as an axis. The two adjustable connections between the extension 16 and the arm 18 and rest 12 respectively provide means whereby the rest 12 can be adjusted into 15 any position in which the user of the telephone finds it most convenient to have the receiver. The front edge 24 of the rest 12 engages the shoulder 25 on the receiver 3 and since said rest fits up around and embraces the side wall of the receiver, the latter will be firmly held in position, and cannot be dislodged from the rest by the pressure of the ear against the receiver.

20 My invention also includes means whereby the hook 4 of the telephone can be depressed thus cutting the telephone out of the circuit without replacing the receiver on the hook. The advantage of this construction is 25 that the receiver may always be retained on the rest 12 and the telephone may be cut into the circuit and cut out therefrom by the mechanism I have provided the operation of which is more simple than that involved in 30 taking the receiver from the hook and placing it on the rest and removing the receiver from the rest and replacing it on the hook again.

In order to depress the hook 4 without 35 hanging the receiver thereon I have provided what I have termed a "hook depressor" which is preferably secured to the supporting arm 13 and by which the hook can be depressed or released. This hook depressor is herein shown as a hook-depressing 40 lever 26 that is suitably pivoted at 27 to a support 28 that is secured to the telephone stand. In the present embodiment of my invention this support 28 is fastened to and 45 sustained by the supporting arm 13, said support 28 being provided at its upper end with a laterally bent forked portion 29 which engages the supporting arm 13 and is clamped thereto by means of a clamping 50 screw 30. This support 28 is also preferably provided with two laterally extending arms 31 which embrace the outer end of the stand 1, and which not only serve to hold the support 28 rigidly in its proper position but 55 also assist in holding the entire support 13 in proper position.

The hook-depressing arm 26 is shown as provided at its upper end with a thumb piece 32 by which it may be turned and at its 60 lower end it is formed with the cam surface 33 adapted to engage the hook 4 when said lever is swung from the open position, Fig. 4 to the closed position Fig. 1. When the hook-depressing lever 26 is in the open position Fig. 4, the hook 4 will be in its ele-

vated position thus connecting the telephone into the circuit as usual. When the hook-depressing lever is swung into its vertical position the cam surface 33 thereon engages the hook 4 and depresses the latter thereby cutting the telephone out of the circuit. The hook depressing lever is formed at its end with a holding surface 34 which rests on the top of the hook 4 when the lever is in its vertical position thereby locking the hook 75 depressed. This portion 34 is situated at one side of the pivot 27 so that the pressure of the hook against the portion 34 will serve to hold the lever 26 in its hook-depressing position.

I will preferably provide an indicator for use in connection with the hook-depressing lever 26 to indicate to the operator whether the hook is depressed or raised thereby to indicate whether the telephone is connected or disconnected. This indicator can conveniently be associated with the thumb piece 32 in such a way that when the lever 26 is raised the indicator will show that the hook is depressed and that the telephone circuit is 90 open, while when the lever is swung forwardly the indicator will show that the hook is elevated and that the telephone circuit is closed.

95 There are various forms which this indicator might assume. As it is shown in the drawings, the thumb piece 32 has associated therewith a block 35 provided with the two faces 36 and 37 on which are the words "Disconnected" and "Connected" or some other words to indicate whether the hook is depressed or raised. This block is so constructed that when the lever 26 is in hook-depressing position as shown in Fig. 1 the face 36 carrying the word "Disconnected" 100 will be in front or exposed to view while when the lever is swung forwardly to allow the hook to rise thereby closing the circuit the face 37 bearing the word "Connected" 105 will be visible. It will thus be seen that with 110 my invention the receiver 3 may be left in the rest 12 at all times if desired and the telephone can be connected to or disconnected from the circuit by operating the lever 26.

115 My invention is simple and inexpensive to manufacture and may be applied to any telephone.

While I have illustrated herein the preferred embodiment of my invention I do not wish to be limited to the constructural features shown.

Having fully described my invention what I claim as new and desire to secure by Letters Patent is:

the ears of the supporting stand, an extension pivotally and adjustably secured to said supporting arm for adjustment in a horizontal position and a receiver rest secured to the 5 end of said extension.

2. A telephone receiver support comprising a supporting arm having one end forked and adapted to embrace the pivotal clamping pin which connects the transmitter to its 10 supporting stand and to be clamped against the ears of the supporting stand, an extension pivotally and adjustably secured to said supporting arm for adjustment in a horizontal position and a receiver rest pivotally and 15 adjustably secured to said extension.

3. A telephone receiver support comprising a supporting arm having one end forked and adapted to embrace the pivotal clamping pin which connects the transmitter to its 20 supporting stand and to be clamped against the ears of the supporting stand, an extension pivotally and adjustably secured to said supporting arm for adjustment in a horizontal position, said extension having a down-turned end, a receiver rest provided with a 25 down-turned slotted arm which engages the down-turned end of the extension and a clamping screw extending through said down-turned arm and down-turned end and 30 adjustably clamping them together.

4. The combination with a telephone set comprising a stand having two ears provided with extensions, a telephone transmitter and frictional clamping means for pivotally connecting the transmitter to the stand 35 and holding it in adjusted position, of a receiver support comprising a supporting arm having a forked end which is frictionally held between clamping surfaces of said clamping device and which is provided with 40 lugs to embrace the extension on one of said ears and a receiver rest secured to said arm.

5. The combination with a telephone desk stand, of a telephone receiver support comprising a supporting arm having provision 45 for attachment to said stand, a receiver rest sustained by said arm, an arm secured to and depending from said supporting arm and a hook-depressing lever pivoted to said arm, said arm having fingers to embrace the 50 stand, whereby said extension is maintained in proper position.

In testimony whereof, I have signed my name to this specification, in the presence of two subscribing witnesses.

HENRY W. MÜNCH.
